SILO FILLER

Filed Dec. 5, 1930

INVENTOR,
SHERMAN C. HETH,
BY *James A. Walsh*,
ATTORNEY

UNITED STATES PATENT OFFICE

SHERMAN C. HETH, OF RACINE, WISCONSIN, ASSIGNOR TO J. I. CASE COMPANY, OF RACINE, WISCONSIN, A CORPORATION

SILO FILLER

Application filed December 5, 1930. Serial No. 500,259.

My invention relates to silo fillers, and particularly to the pipes thereof, which I so improve as to render them more effective under the varying conditions commonly incident to the operation of such machines, whereby the long filler pipe can be readily disconnected from the fan casing to remove clogged material therefrom, and as readily returned to normal position, as well as otherwise adjusted, while other advantages will be apparent from the following description.

In the accompanying drawing, forming part hereof, Figure 1 is a rear elevation of a portion of the fan casing, which terminates in a boot as is common, and to which a pipe section is connected; Fig. 2, a side elevation of said structure and to which my improvements are applicable; Figs. 3 and 4, detail elevations illustrating the adjustability of the piping; Fig. 5, a side elevation of a silo and filler illustrating the application of my improvement; and Fig. 6 is a horizontal sectional view taken on the dotted line 6—6 in Fig. 5.

In said drawing the numeral 5 indicates a fragmentary portion of the fan casing, and 6 a boot therefor, which is provided with a reinforcing flanged ring 7. It is customary to attach a short pipe section 8 to the boot 6 by securing its lower flanged ring 9 to the ring 7 by means of bolts, while the lower member 10 of the upper pipe sections is bolted and supported by the flanged ring 11 at the upper end of the outlet 8 in which manner the silo pipe becomes a continuous structure bolted or otherwise connected together section by section. In my improvement, however, it will be noted that the lower end of the section 8 is pivotally connected, at 12, to its ring 9 at diametrically opposite sides, by which means the section, as well as the remainder of the pipe supported thereby, may be rocked from side to side, and that its upper end is also pivoted, at 13, to the upper ring 11 so that it may be swung slightly in a forward and backward direction in relation to the silo, whereby said section is capable of variable movements and is in effect what is commonly called a universal pipe joint, the function of which will appear. Instead of securing the boot and outlet together by rings and bolts I connect these

sections by means of a collar 15 loosely mounted on section 8 and which is provided at opposite sides with clamping links 16 pivotally secured to adjustable hangers 17. When fastening the rings 7, 9, said collar is slipped down thereover to occupy the position indicated by full lines in Fig. 2, when the links 16 are brought about the cams 19 of levers 20, which latter when turned in the direction required tightly draw the links sufficiently to effectively bind the collar 15 about the rings, but it will be understood that any practical means may be employed for detachably assembling the collar and meeting ends of said sections.

As is well known, silage is of a heavy and sluggish character, and during the operation of cutting and discharging into the silo, 25 it must be forcibly propelled a comparatively long distance, and occasionally the material becomes packed and chokes the piping, in which circumstance it is necessary to disconnect the outlet 8 from the boot 6 and relieve the choked condition by suitable implements, and then bolt the parts together. 75 With my improvement, however, it is but a simple matter to manipulate the levers 20 to release links 16 when the ring may be raised to the position indicated by dotted lines in Fig. 2 and suspended by the links, which are 80 swung upwardly to engage hooks 21 on the side of the outlet section whereupon the outlet 8 supporting the upper pipe sections can be readily shifted and supported on the boot 6 as indicated in Fig. 3 and ready access thus 85 obtained to the boot or piping for removing packed material therefrom. In some circumstances, however, it will not be necessary to fasten the collar 15, as when it is positioned to overlap the meeting ends 7, 9, it will have 90 served to center a section as 8 in relation to the boot 6 or other section, and prevent lateral displacement of such section; and further, when thus assembled, the relation of said centering collar to the rings 7, 9, affords a turn-table action whereby the long discharge pipe 10 may be rotated within the collar so that its distributing portion 10' may be adjusted to varying positions as indicated by the dotted lines in Fig. 6.

It will also be understood that frequently because of sloping or other unfavorable ground conditions a silo filler, as commonly assembled, cannot be set perfectly level and therefore it becomes difficult to attach and properly position the piping (which is assembled and bolted on the ground and then elevated by tackle), but by providing the section 8 in pivotal relation to both the boot 6 and the piping 10 such flexible connection permits adjustability of the upper piping, so that if conditions require it may be set at angular positions between the fan casing and the silo inlet 26, or the joint 8 may be adjusted at an angle to compensate for any irregular positioning of the filler 27, and angular positions laterally of pipe 10 relative to the silo thus avoided. As the piping 10 is thus flexibly connected to the boot 6 in the manner described it will be apparent that said piping may be leaned in different directions according to ground and other conditions to accommodate the silo filler 27 in relation to the silo 25, many of which silos, as indicated in Fig. 5, embody projecting bases, as 28, which prevent the filler from being set closely adjacent thereto, and therefore by being enabled to adjust the long piping laterally and farther from and closer to the silo exact alinement of the filler with the silo inlet 26 is not required, and said filler may therefore be set according to the most favorable ground and other conditions present. In filling a silo (approximately 15 ft. in diameter) with the discharge end of the piping unadjustable because of bolting the various sections together and to the fan casing it becomes necessary for one or two attendants in the silo to fork and evenly spread the silage, which discharges in one area only, but by employing a turntable joint substantially as described between the meeting ends of two sections the long piping 10 may be rotated to position the distributor 10' in varying directions, for example, as indicated by the dotted lines in Fig. 6. A wide distribution of the material is thus obtained, and, as the distributor is usually in hinged sections the outer section may be elevated to direct material to the opposite side of the silo, so that the deposit will be of a uniform character and not require the manual labor referred to.

I claim as my invention:

1. In a silo filler, a fan casing having a discharge outlet, a pipe adapted to discharge into a silo, an intermediate pipe section between said casing and discharge pipe, a collar loosely mounted on the intermediate section for connecting the latter to the outlet, and means for securing the collar, intermediate and outlet sections together and whereby the intermediate and outlet sections may be wholly disengaged and the intermediate section shifted on the edge of and sustained by the discharge outlet.

2. In a machine of the character described having a fan casing embodying a flanged ring, a pipe section having a flanged ring adapted to be moved upon and rest on said first mentioned ring, a movable collar on the pipe section adapted to be overlapped on said rings when the latter are in alinement, and means on the fan casing for fastening the collar about the rings and whereby the collar may be wholly disengaged so that the pipe section and parts associated therewith may be shifted on the fan casing ring and sustained in various positions.

3. In a machine of the character described, a fan casing, a discharge pipe adapted to be connected to the casing and composed of sections, means for connecting two of said sections whereby the pipe may be adjusted to leaning position, and a collar loosely mounted on one of the sections and adjustable on the meeting ends of said latter section and the fan casing so that the section may be centered upon the fan casing and the upper portion of the pipe rotated to vary the position of its discharge end.

In testimony whereof I affix my signature.
SHERMAN C. HETH.
